UNITED STATES PATENT OFFICE.

FREDERICH W. WOOD, OF KANSAS CITY, MISSOURI, ASSIGNOR TO BERRY-WOOD PIANO
PLAYER CO., OF KANSAS CITY, MISSOURI.

TRACKER-BAR FOR PIANO-PLAYERS.

No. 872,815.

Specification of Letters Patent.

Patented Nov. 26, 1907.

Application filed December 14, 1906. Serial No. 347,899.

To all whom it may concern:

Be it known that I, FREDERICH W. WOOD, a citizen of the United States, residing at Kansas City, in the county of Jackson and State of Missouri, have invented certain new and useful Improvements in Tracker-Bars for Piano-Players, of which the following is a specification.

This invention relates to tracker bars for pneumatically played instruments, and has for its object to produce a device of this character having supplemental tubes and adjustable means for varying the relation between said supplemental tubes and the note sheet 15 adapted to travel over the tracker bar.

A further object is to produce a device of this character of simple, durable and inexpensive construction.

To these ends the invention consists in 20 certain novel and peculiar features of construction as hereinafter described and claimed; and in order that it may be fully understood reference is to be had to the accompanying drawing, in which—

25 Figure 1, is a side view of a tracker-bar equipped with my improvement, a portion of the bar, the improvements thereon and the note sheet, being shown in vertical section. Fig. 2, is a similar view except that the improvements are in duplicate, one being located at each end of the bar and each provided with but a single opening. Fig. 3, is a 30 end view of the tracker-bar. Fig. 4, is a detail perspective view of part of the attachment constituting my improvement.

Before proceeding with a detailed description of the invention it is desirable to state that the supplemental tubes are intended under certain conditions to conduct air to 40 certain instrumentalities forming no part of this invention, whereby the note sheet on shifting laterally in one direction or the other out of its direct and proper path is caused to reverse such shifting movement, the result 45 being that the note sheet is compelled to travel its predetermined course and always track properly with the regular tracker bar openings.

Referring now to the drawing, 1 indicates 50 a tracker bar of any suitable or preferred type and 2 the note sheet extending transversely thereover in the usual manner, the perforations (not shown) of the note sheet being adapted to register with the proper tracker bar openings, 3, in such passage to permit

air to enter such openings and pass through the flexible tubes 4, for a purpose not necessary to name herein. In Fig. 1 the tracker bar is provided in its upper side and one end with a longitudinally extending groove 5 of 60 inverted-T shaped by preference, with a vertical slot 6 connected to said groove and by preference with an opening or recess 7 communicating with the lower end of said slot.

8 indicates a slide of proper form to fit 65 snugly and slidingly in said groove and provided with a pair of openings or passages 9 and a pair of tubes 10 communicating with said openings and depending by preference through slot 6, the lower ends of tubes 10 being engaged by flexible tubes 11 which lead to instrumentalities for effecting directly or indirectly, lateral movement of the note sheet on the tracker-bar in one direction or the other. In the construction shown in 70 Fig. 1, the note sheet by preference normally covers the inner opening or passage 9 but leaves uncovered the companion opening or passage. As long as the note sheet maintains the relation described it is tracking 75 properly. Should it shift to the right, however, and cover the normally uncovered supplemental opening, certain means hereinbefore referred to as forming no part of the invention, shift it to the left until it uncovers 80 said opening. Should the note sheet shift to the left and uncover the normally covered supplemental opening other instrumentalities shift it back again to the right.

In Fig. 2, which illustrates a slide at each 85 end of the tracker bar and said slide as equipped with a single supplemental opening, the note-sheet is shown as terminating just inward of said openings, both of which therefore correspond in function to the outer 90 opening 9 of Fig. 1. If desired both openings 9 of Fig. 2 may correspond to the inner opening 9 of Fig. 1, in which case both of said opening should be normally covered by the note-sheet. If both supplemental openings of Fig. 2, correspond to the outer opening of Fig. 1, and the note-sheet shifts and covers one of them this action results, through the instrumentalities referred to, in shifting 95 the note-sheet in the opposite direction. If 100 both supplemental openings in Fig. 2 should correspond to the inner opening of Fig. 1, and the note sheet shift to the right or to the left and therefore uncover the left hand or the right hand supplemental opening, re- 110

spectively, the result will be that the note-sheet will be shifted back to its original position. My preferred means for effecting the shifting of the note-sheet are described and 5 illustrated in an application now pending in the U. S. Patent Office, which application also shows and describes slides of the character embodied in this application which, therefore, is confined as regards its claims, to 10 the specific construction of the slide or slides and the means whereby each slide is adjusted longitudinally of the tracker bar for the purpose of accommodating the note sheet in case its width varies under expansion or contraction or by reason of its edges being curled or doubled back upon the body of the sheet.

The slide is provided at its outer end with a groove 12 of T-shape in cross section, the 20 stem-portion of the groove opening out through the end of the block to receive the neck 13 of the set screw 14, the inner end of the screw being provided with a head 15 occupying the head of the T-shaped groove. 25 The screw is mounted in a screw seat in the bracket 16 secured to or formed rigidly with the support 17. From the foregoing it will be seen that the screw bears a swivel relation with respect to the slide, so that when it is 30 turned in one direction or the other it effects longitudinal adjustment of the slide inward or outward and thus changes the relation of the supplemental opening or openings of the tracker bar with respect to the note sheet.

35 From the above description it will be apparent that I have produced a tracker bar for pneumatically played instruments possessing the features of advantage enumerated and I wish it to be understood that I do

not desire to be restricted to the exact details of construction shown and described as obvious modifications will suggest themselves to one skilled in the art. 40

Having thus described the invention what I claim as new and desire to secure by Letters Patent is:—

1. In a device of the character described, a tracker bar provided with a longitudinal series of air ducts and with an opening at one end of said series, a block fitting in said opening and having one of its faces flush with and forming practically a continuation of the face of the tracker bar; said block having a passage extending through it from said face, and means to adjust said block longitudinally in the opening of the tracker bar so as to vary the distance between the mouth of said passage and the series of tracker bar air ducts. 50

2. In a device of the character described, a tracker bar provided with a longitudinal series of air ducts and with an opening at one end of said series, a block fitting in said opening and having one of its faces flush with and forming practically a continuation of the 55 face of the tracker bar; said block having a passage extending through it from said face, and a screw suitably supported and engaging said block to adjust the same longitudinally and thus vary the distance between its passage and the longitudinal series of tracker bar air ducts. 70

In testimony whereof I affix my signature, in the presence of two witnesses.

FREDERICH W. WOOD.
